UNITED STATES PATENT OFFICE.

WILLIAM R. SCHWAB, OF KANSAS CITY, MISSOURI, ASSIGNOR TO THE CAMERAGRAPH COMPANY, OF KANSAS CITY, MISSOURI, A CORPORATION OF ARIZONA.

REWINDING DEVICE.

1,115,586.

Specification of Letters Patent.

Patented Nov. 3, 1914.

Application filed January 6, 1913. Serial No. 740,503.

To all whom it may concern:

Be it known that I, WILLIAM R. SCHWAB, a citizen of the United States, residing at Kansas City, in the county of Jackson and State of Missouri, have invented new and useful Improvements in Rewinding Devices, of which the following is a specification.

This invention relates to improvements in apparatus for feeding or otherwise handling strips or webs of paper or other materials from a source of supply such for example as a roll, and the primary object of the invention is to provide a device for controlling the backward movement or rewind 10 of the strip or web whereby the forward edge thereof may be easily and quickly returned to a predetermined point after having been advanced beyond such point.

While the invention is applicable generally to the uses above stated, it is especially applicable to the paper-feeding mechanism of a photographic machine, such for example as that disclosed in my prior application, Serial No. 662,478 filed November 25, 1911, the rewinding device enabling the strip or web to be quickly and easily returned to a point where its forward edge just projects through the feeding rollers irrespective of the length of paper that has been fed by 20 these rollers, within a certain limit, thereby enabling the machine to be opened to permit access to the interior thereof and also enabling the roll-holding receptacle to be removed without wasting the sensitized 30 paper by exposure, as well as avoiding unthreading of the strip or web relatively to the rollers or devices which guide and feed the same within the machine.

To these and other ends, the invention 40 consists in certain improvements, and combinations and arrangements of parts, all as will be hereinafter more fully described, the novel features being pointed out particularly in the claims at the end of the specification.

In the accompanying drawings:—Figure 1 represents a vertical section of a rewinding device embodying the present invention, the parts being shown in the position which 50 they occupy normally while the strip or web is being fed forward or advanced. Fig. 2 is a view similar to Fig. 1 but showing the strip or web rewound, and showing the parts in the relative positions which they occupy 55 after rewinding of the strip or web; Fig.

3 shows the rewinding device as viewed from the right in Fig. 1, with the rear wall of the casing removed; Fig. 4 is a perspective view showing the controlling cam and the adjustable stop; Figs. 5 and 6 are detail 60 perspective views of the elements of a friction clutch which serve to drive the cam; Fig. 7 is a detail sectional view of the handle or knob which serves to turn the roll in a backward direction to rewind the strip or 65 web.

Similar parts are designated by the same reference characters in the several views.

While this invention may be used in various instances where it is desirable or necessary to rewind a strip or web so that its forward edge may be returned to a predetermined point after being advanced different distances, the invention in the present embodiment thereof is shown in connection with the paper-feeding mechanism of the type used on photographic exposing and developing machines. This embodiment of the invention, however, is to be understood as an example thereof, as equivalent 80 constructions may be devised by those skilled in the art which will embody the principles of the invention and will be included within the scope of the claims at the end of the specification.

In the present instance, 1 designates the upper portion of the casing of a machine of the type, for example, of those used for exposing successive sections or portions of a strip or web of photographic material for 90 the purpose of making reproductions, the space 2 representing, for example, the vertical dimension of the optical field. The strip or web 3 of sensitized material is advanced to bring sections thereof successively into the optical field by coöperating feed rollers 4 between which the strip or web passes. The strip or web in the present instance is wound into a roll 5 and the roll is adapted to be inserted within and closed by a receptacle or casing 6. The roll is preferably wound on a spool which has flanges 7 at the ends and journals 8, the latter serving to revolubly support the spool. In order to facilitate insertion and removal of the spool relatively to the casing, the latter is provided in the present instance with guides 9 which are fixed to the opposite walls thereof, and slides 10 are adapted to coöperate with the guides and to 110

also coöperate with the journals 8 of the spool and thereby support the latter revolvably within the casing. One of the journals 8 of the spool is provided with a clutch jaw 11 which provides means for rotating the spool backwardly and thereby rewinding the strip or web thereon. A rewinding handle or knob is provided whereby the spool may be rotated in a backward direction to 10 wind the strip or web, and preferably, this rewinding handle or knob is disconnected from the spool. In the present instance, a knob or handle 12 is provided which is arranged exteriorly of the receptacle or casing 6, this knob or handle being fixed to a square or angular shaft 13 and this shaft 13 passes through the hub 14 of a ratchet wheel 15. The ratchet wheel 15 is located interiorly of the casing and its sleeve-like hub 14 is journaled to revolve in a bearing 16 which is fixed to the adjacent wall of the casing, and the shaft 13 which is fixed to the handle 12 is connected to revolve with the ratchet wheel 15 although it is capable of 25 axial movement through the hub thereof whereby the clutch jaw 17 formed on the inner end of the shaft 13 may be caused to engage and disengage relatively to the clutch jaw 11 on the respective journal of 30 the spool. Normally, however, the shaft 13 is held in retracted position so that it will be disconnected from the spool, and for this purpose a compression spring 18 may be interposed between the handle or knob 12 and 35 a collar 19 attached to the hub of the ratchet wheel. The strip or web 3 preferably co-operates with a pair of guiding and tensioning rollers 20 and 21 which are interposed between the spool and the feed rollers 4, the roller 20 in the present instance being journaled in a bracket 22 which projects into the casing 6 from a panel 23 which is removably fitted to the front of the casing to permit insertion and removal of the paper 45 rolls, and this panel may be retained in closed position by a lock or equivalent device 24. The roller 21 is preferably journaled directly in the casing 6 and adjacent to an aperture 25 in the bottom of the casing through which the strip or web passes on its way to the machine wherein the paper is to be used.

Ordinarily, the strip or web is fed by the rollers 4 intermittently so as to bring portions or sections thereof successively into the optical field, the spool being free to rotate and thus supply the paper from the roll thereon. It is desirable or necessary, however, to occasionally open the machine 55 to obtain access to the interior thereof and to also remove a casing or receptacle containing paper of one width and to substitute a casing containing paper of a different width. In each of these instances, there 60 would be a loss of paper equivalent to the length thereof which had been fed beyond the rollers 4, and where the machine was being operated to expose sections of the paper equivalent to the vertical dimension of the optical field, the loss of paper occasioned in 70 that way would be equivalent to the area of the optical field. The present invention provides means for automatically controlling the rewinding of the strip or web upon the roll whereby the forward edge of the 75 strip or web will be returned to a point where the loss of paper, due to exposure, is reduced to a minimum and liability of the strip or web becoming unthreaded from the feeding and guiding rollers is avoided. This 80 controlling means in the present instance embodies a pawl 26 which is adapted to co-operate with the ratchet wheel 15, this pawl being pivoted within the casing 6 at 27 and is provided with a projection 28 which is 85 arranged to coöperate with a cam 29, the projection 28 being retained in coöperative relation with the cam by a spring 30 which acts on the pawl 26. The cam 29 is formed with a depression 31 which, when the strip 90 or web has been rewound to a predetermined point, will receive the projection 28 on the pawl 26 and thereby permit the latter to move into engagement with the ratchet wheel 15 and thereby lock the rewinding 95 handle or knob 12, a concentric portion 32 on the cam forming a surface on which the projection 28 may ride, thereby holding the pawl 26 in disengaged relation to the ratchet wheel, and a stop 33 is provided which is 100 adapted to be engaged by the projection 28 on the pawl whereby rotation of the cam in a forward direction is arrested. This stop 33 is adjustable in a direction circumferentially of the cam whereby the rewinding device may be set to rewind different lengths of the strip or web, the length of the strip or web to be rewound being usually determined by the vertical dimension of the optical field. In the present instance, the periphery of the cam is provided with threaded holes 34 which are suitably spaced circumferentially thereof, and any one of these holes may receive a screw 35 which serves to 105 secure the stop 33 to the cam. In order to provide for adjustments of the stop 33 intermediate of those afforded by the holes 34, the stop may be provided with a circumferentially extending slot 36 through which the screw extends. The cam 29 is loosely mounted on a shaft 37, this shaft being journaled at one end in a bearing 38 which is secured to one of the side walls of the casing, and the opposite end of the shaft is journaled in a bracket 39 which latter is fixed within the casing. The inner side of the cam 29 is smoothed to provide one member of a friction clutch, the other member 40 of the friction clutch being opposed to this smooth side of the cam, and a disk 41 110

115

120

125

130

of suitable friction material is interposed between the cam and the member 40. The member 40 of the clutch is mounted to turn with the shaft 37, although it is capable of axial movement with respect thereto. In the construction shown, the hub 42 of the clutch member 40 has a square or angular opening which forms a spline connection with the squared hub 43 of a disk 44, the latter being fixed to the shaft 37 by a set-screw 45 or equivalent means. A compression spring 46 is interposed between the movable clutch member 40 and the relatively fixed disk 44, and its expansive tendency 15 serves to press the clutch member 40 and the friction material 41 against the cam 29 with sufficient force to turn the latter until the stop 33 thereon is brought against the projection 28 on the pawl, whereupon 20 further rotation of the shaft 37 may occur, although the cam will remain stationary.

The shaft 37 and consequently the cam are rotated at a rate which is directly proportional to the rate of movement of the strip or web while the same is being moved either in a forward or a backward direction, and the present invention provides means for accomplishing this movement of the shaft 37 and the cam irrespective of the diminishing 30 diameter of the roll due to the unwinding of the paper therefrom. In the construction shown, a wheel 47 is employed which bears against the periphery of the roll and has a rolling contact therewith, the wheel being 35 preferably provided with a tire of rubber or other suitable material that will afford the necessary degree of friction to avoid slippage. This wheel is mounted on a shaft 48 which latter is journaled in a swinging arm 49 whereby the wheel will remain in rolling 40 engagement with the periphery of the paper roll irrespective of the diameter thereof, and a suitable spring 50 serves to yieldably press the wheel against the periphery of the roll. 45 Motion is communicated from the wheel 47 to the shaft 37 by a bevel gear 51 which is fixed to the wheel 47 and co-operates with a bevel gear 52 fixed to a shaft 53, the latter being journaled at its ends in the swinging 50 arm 49 and has a bevel gear 54 fixed thereto which co-operates with a bevel gear 55, the latter being fixed to the shaft 37. As the arm 49 swings about the shaft 37 as an axis, the driving connection between the wheel 47 and the shaft 37 will be maintained irrespective 55 of the position occupied by the swinging arm.

Fig. 1 shows the relation of the parts while the strip or web is being advanced or 60 fed in a forward direction, the wheel 47 being then rotated in the direction indicated by the arrow and tending to rotate the cam 29 in the direction indicated by the arrow. The advance of the strip or web will rotate 65 the cam 29 until a length of paper has been

advanced which corresponds, for example, to the vertical dimension of the optical field, and when this point has been reached, the stop 33 on the cam will abut against the projection 28 on the pawl 26, the cam being 70 thereby held from rotation, and further rotation of the shaft 37 will cause slippage between the cam and the friction clutch member 40. As the projection 28 on the pawl will then rest on the concentric portion 32 75 of the cam, the pawl will be in disengaged relation from the ratchet wheel 15, as shown in Fig. 1. When, however, it is desired to rewind the strip or web, it is only necessary to push the knob or handle 12 inwardly so 80 as to engage the clutch jaw 17 thereon with the clutch jaw 11 on the spool, and to turn the knob or handle to the right, the rewinding knob or handle being then connected to the spool, and as the pawl 26 is disengaged from 85 the ratchet wheel 15, the spool may be turned backwardly to rewind the strip or web. This rewinding operation may continue until the projection 28 on the pawl has reached and entered the depression 31 in the cam, 90 whereupon the pawl 26 will be moved by its spring into locking engagement with the ratchet wheel 15 and thereby prevent further rotation of the spool in a backward direction. By setting the stop 33 on the cam 95 in such a position that the circumferential distance between it and the depression 31 is proportionate to the distance the strip or web is advanced at each operation, the controlling device will enable the strip or web 100 to be rewound to a predetermined point irrespective of whether the strip has been advanced a distance equal to the total dimension of the optical field or any intermediate distance, and the automatic locking of the 105 spool when this point has been reached prevents continued rewinding of the strip which would cause it to be unthreaded from the feeding and guiding rollers.

I claim as my invention:—

1. The combination of means for feeding a strip of material in one direction, means for moving said strip in a reverse direction, and means controlled by the movement of the strip to automatically arrest the 115 reverse movement of the strip at a predetermined point.

2. The combination of means for advancing a strip of material, means for moving said strip in a backward direction to rewind 120 the same, and means controlled by the advancing movement of the strip for arresting the backward movement thereof after a measured length of the strip has been rewound.

3. The combination of rollers having means for operating them to feed a strip of material between them, means for moving the strip backwardly, and means co-operative with the strip to arrest the backward 130

- movement of the strip automatically after a measured length thereof has been moved backwardly between the feeding rollers to prevent withdrawal of the strip from between the feeding rollers.
4. The combination of means for unwinding a strip from a roll, means for rewinding the strip thereon, and measuring means adapted to coöperate with the periphery of the roll and operative to automatically limit the rewinding movement thereof.
5. The combination of means for unwinding and feeding a strip from a roll, means for turning the roll to rewind the strip thereon, a locking device operative to prevent rewinding movement of the roll, and a measuring wheel coöoperative with the strip to control the locking device.
6. The combination of means for feeding a strip from a roll, means for rewinding the strip on the roll, a locking device operative to prevent rewinding movement of the roll, and means governed by the movement of the strip for rendering the locking device inoperative until the strip has been rewound to a predetermined point.
7. The combination of means for feeding a strip from a roll, means for rewinding the strip on the roll, a locking device operative to prevent rewinding movement of the roll, and means embodying a wheel having a rolling engagement with the periphery of the roll for controlling the locking device.
8. The combination of means for feeding a strip from a roll, means for rewinding the strip on the roll, a locking device operative to prevent rewinding movement of the roll, and means embodying a wheel having a rolling engagement with the periphery of the roll, and a cam operative by said wheel for automatically arresting the rewinding movement of the roll at a predetermined point.
9. The combination of means for feeding a strip from a roll, means for rewinding the strip on the roll, a locking device operative to prevent rewinding movement of the roll, and means embodying a cam coöoperative with the locking device, and means governed by the rewinding movement of the strip for actuating said cam.
10. The combination of means for feeding a strip from a roll, means for rewinding the strip on the roll, a locking device operative to prevent rewinding movement of
- the roll, and means embodying a cam coöoperative with the locking device, and means governed by the rewinding movement of the strip for frictionally driving 60 said cam.
11. The combination of means for feeding a strip from a roll, means for rewinding the strip on the roll, a locking device operative to prevent rewinding movement of the roll, 65 and means embodying a wheel having a rolling engagement with the periphery of the roll and yieldably held in contact therewith for rendering the locking device inoperative until the strip has been rewound 70 to a predetermined point.
12. The combination of means for feeding a strip from a roll, means for rewinding the strip on the roll, a locking device operative to prevent rewinding movement of the roll, 75 and means embodying a cam having means for moving it at a rate proportional to the movement of the strip and coöoperative with the locking device to hold the same in inoperative condition until the strip has been 80 rewound to a predetermined point.
13. The combination of means for feeding a strip from a roll, means for rewinding the strip on the roll, a locking device operative to prevent rewinding movement of the roll, 85 and means embodying a cam having means for moving it at a rate proportional to the movement of the strip and coöoperative with the locking device to hold the same in inoperative condition until the strip has been 90 rewound to a predetermined point, and an adjustable stop on the cam for setting the same to permit rewinding varying lengths of the strip.
14. The combination of means for feeding 95 a strip from a roll, means for rewinding the strip on the roll, a locking device operative to prevent rewinding movement of the roll, and means for controlling the locking device embodying a cam coöoperative with the 100 locking device, a wheel having a rolling engagement with the periphery of the roll, and a friction clutch forming an operative connection between said wheel and clutch.
- In testimony whereof I have hereunto set 105 my hand in presence of two subscribing witnesses.
